UNITED STATES PATENT OFFICE.

EDWIN O. ROOD, OF MAPLE PARK, ASSIGNOR TO E. O. ROOD & CO., OF CHICAGO, ILLINOIS.

COMBINED IRONING-TABLE AND CLOTHES-RACK.

SPECIFICATION forming part of Letters Patent No. 415,562, dated November 19, 1889.

Application filed April 3, 1889, Serial No. 305,862. (No model.)

To all whom it may concern:

Be it known that I, EDWIN O. ROOD, a citizen of the United States, residing at Maple Park, in the county of Kane and State of Illinois, have invented a new and useful Improvement in Combined Ironing-Table and Clothes-Rack, which improvement is fully set forth in the following specification and accompanying drawings.

10 My invention consists of a combined ironing-table and clothes-rack constructed, combined, and operating as hereinafter fully set forth and claimed.

15 Figures 1 and 2 represent perspective views of a combined ironing-table and clothes-rack embodying my invention, the same being in respectively open and closed positions.

Similar letters of reference indicate corresponding parts in the two figures.

20 Referring to the drawings, A designates an ironing-board, which is hinged to the ledge B, attached to the legs F of the frame C. Secured to the top of the leg D of the frame is a cross-piece E, which is adapted to sustain 25 the free end of the board, or end opposite to the hinges thereof. The legs F are extended above the ironing-board and crossed, their upper ends sustaining the cross-bar G, which, as will be seen, are directly above the ledge B.

30 H H' designate swinging racks for clothes, towels, &c., in the present case four in number, each having the upright H², formed with journals J, whose bearings are in the ledge B and cross-bar G, it being noticed that the 35 journals of the racks H are set forward of the journals of the racks H', and that the racks H' have legs K, which rest on the floor or ground. The cross-piece E has near its ends the shoulders L, and the outer uprights 40 of the racks are recessed, as at M N, so as to engage with said cross-piece.

The racks are provided with hooks or catches P and pins Q, whereby they may be held in closed position. When the ironing board and table are required for service, the 45 catches P are released and the racks are swung out, as seen in Fig. 1, it being noticed that the racks H' abut against the upper parts of the legs F, and the racks H abut 50 against the uprights H² of the racks H'. By these provisions the opening of the racks is properly limited, it being noticed that contiguous racks set at a right angle to each

other, so that each rack is conveniently accessible from both sides. The ironing-board 55 is also accessible, and may be raised as required for the application and removal of shirts, &c., to be ironed, said board, when lowered, having its free end resting firmly on the cross-piece E. The racks H may be 60 closed against the ironing-board when so required, in which position the top walls or shoulders of the recesses M rest on the cross-piece E, thus preventing sagging of said racks. The racks H' may be also closed to- 65 ward the racks H, in which case the shoulders L on the cross-piece E act as a stop to limit the closing motion of said racks H'. The catches P may now be applied, whereby 70 the several parts are held compactly together, and the device may be stowed away or packed, as desired.

Having thus described my invention, what I claim as new, and desire to secure by Letters Patent, is—

75 1. A combined ironing-board and clothes-rack consisting of a frame with a board pivoted to a ledge at one end thereof, a cross-bar secured to said frame above said ledge, racks journaled in said ledge and bar and having legs at their outer ends adapted to sustain them, and racks journaled in said bar and ledge in advance of said first-mentioned racks and adapted to swing at angles to the same, said parts being combined substantially as 80 described.

2. A combined ironing-table and clothes-rack consisting of the frame C, with cross-legs F at one end thereof, the ledge B and cross-bar G, secured to said cross-legs, the 90 cross-bar E at the other end of the frame, and having the shoulders L, and the racks H H', journaled in the said ledge and cross-bar and having notches M and N, respectively, said parts being combined substantially as 95 described.

3. In a combined ironing-table and clothes-rack, the hinged ironing-board, in combination with the cross-piece E, which sustains the free end of said board, and the swinging 100 racks having recesses and engaging with said cross-piece, substantially as described.

EDWIN O. ROOD.
